ASSIGNORS TO UNITED SHOE MACHINERY COMPANY, OF PATERSON, NEW JERSEY,
A CORPORATION OF NEW JERSEY.

BUFFING-MACHINE.

1,157,725.

Specification of Letters Patent. Patented Oct. 26, 1915.

Application filed March 7, 1910. Serial No. 547,904.

To all whom it may concern:

Be it known that we, WILLIAM A. REED and JAMES FOLEY, citizens of the United States, residing at Revere, in the county of 5 Suffolk and Commonwealth of Massachusetts, and Chelsea, in the county of Suffolk and Commonwealth of Massachusetts, respectively, have invented certain Improvements in Buffing-Machines, of which the 10 following description, in connection with the accompanying drawings, is a specification, like reference characters on the drawings indicating like parts in the several figures.

This invention relates to grinding or polishing machines and is herein shown as embodied in a machine for buffing boots and shoes.

In such machines it is customary to make use of a rotary roll covered with an abrasive 20 material and to present the stock, for example, the sole of a shoe, to this roll. It has been found that where longitudinal reciprocation is imparted to such a roll in addition to its rotation, a superior finish is 25 imparted to the surface of the work and that the life of the abrasive covering of the roll is greatly prolonged. Accordingly machines have been designed from time to time in which the roll shaft has been 30 reciprocated as well as rotated. These shafts, however, are heavy; the speed with which it is advantageous to rotate them is high, (varying approximately from three thousand to forty-two hundred revolutions 35 per minute); and the ratio of reciprocation to rotation, in order to produce satisfactory work is approximately one to eight. With a heavy shaft moving at high speed in the manner indicated above it is evident that 40 any looseness which may for any reason develop in the bearings of the shaft or in the reciprocating mechanism will, unless special provision is made, tend rapidly to increase. Hitherto the reciprocation of 45 these shafts has been accomplished by positive actuation first in one direction and then in the other. In the practical construction of such machines a certain small amount of lost motion is almost certain to exist. Even 50 if it does not then exist, it develops soon after the machine is put into use owing to

the wear of the parts; and once having been developed it increases rapidly for the reasons stated above. The disadvantages of such wear manifest themselves particularly 55 in two ways, either one of which is sufficient to destroy the utility of the machine; first the machine soon becomes so noisy as to be unendurable by the operator and second a wavy surface is produced on the work owing 60 to the fact that the roll shaft no longer runs true.

Accordingly one object of this invention consists in a machine in this class of means for automatically taking up lost motion. 65 Any convenient means for accomplishing this result may be employed. In the illustrated embodiment a resilient member holds the bearing parts of the reciprocating mechanism at all times in intimate contact, thereby 70 by obviating all pounding with its resultant noise and wear; and preferably the shaft itself is held between a positively actuated member and the resilient member so that it is positively actuated in one direction and 75 yieldingly in the other.

In a high speed device of this type wherein in a rotating shaft is also reciprocated excessive friction is liable to occur between the shaft (or some part fast to it) and the 80 member which causes said shaft to be reciprocated, this friction being due to the fact that the end (or some part) of the heavy, rapidly rotating shaft, at the moment of its reversal of direction of motion, grinds 85 against the reciprocating mechanism with great force. Accordingly in order to minimize this tendency and to promote still further the smooth running qualities of the machine, another object of this invention consists in the provision of a ball the approximate center of which is located in the axis of said shaft, and in the preferred embodiment two such balls are provided one at each end of the shaft. With this construction the excessive grinding action above referred to is largely obviated.

It is desirable that these balls be thoroughly lubricated, and another object of this invention consists in the provision of 100 suitable oil receptacles and passages.

These and other features of the invention

including certain details of construction and combinations of parts will be described in connection with the accompanying drawing and pointed out in the appended claims.

5 Referring now to the accompanying drawings, Figure 1 is a front elevation of a buffing machine embodying the invention; Fig. 2 is a view partially in section showing the reciprocating mechanism more in detail.

10 Mounted in the lower bearings of the frame 1 is a counter-shaft 2 to which power is applied as desired by a belt (not shown) which is adapted to engage fast and loose pulleys 3 and 4. Said counter-shaft carries 15 also a pulley 5 from which the shank-out pad 6 is driven, an eccentric encircled by a strap 7 from which the rod 8 is actuated, and a pulley 9 from which the roll shaft 14 is rotated. Said roll shaft is 20 slidably and rotatably mounted in bearings 10 and 11, and carries two operating members 12 and 13, herein shown as buffering rolls. Preferably this roll shaft is hollow, as shown in Fig. 2, and one end is counter-bored to receive a disk 15 which takes the 25 thrust of a cushioning device herein shown as a coiled spring 16. Contacting with the opposite end of said spring and having a guiding projection extending into the coils 30 thereof is a support 17 which is free to rotate as well as to move longitudinally with respect to the roll shaft. Said support is formed at the center of its outer portion with a spherical socket and carries therein 35 a ball 18. In order to provide a rigid abutment for said ball, and likewise for said support and spring, a plug 19, having a shallow socket to receive said ball, is carried by an extension 20 of the bearing 11, 40 said plug being adjustable to vary the tension of said spring and being held in adjusted position by a set screw 21. To the opposite end of the shaft a pulley 22 is fastened by means of a tapered pin 23; and 45 held rigid with said pulley, and hence with said shaft, is a disk 24 which carries a ball 25 similar to the ball 18. In order to move said shaft in opposition to said spring a bell-crank lever 26 is pivoted at 27 to a 50 bracket 28, said lever carrying a hardened plug 29 having a shallow concave socket to receive said ball. Actuation of the bell-crank lever is accomplished by means of the rod 8 which is connected by a swivel joint 55 with the forked arm 29 of said lever. The pulley 22 is rotated by a belt 30 which passes around the pulley 9.

With regard to the advantages of this construction, it should be noted that the 60 spring is effective in all positions of the shaft since said spring is made strong enough to hold the coöperating parts of the respective bearings at all times in intimate contact. Consequently if some part of the

reciprocating mechanism, for example, the 65 pin 27, becomes worn the spring will automatically take up the lost motion which would otherwise result and will thus minimize the tendency to further wear. It should also be noted that the balls 18 and 70 25 which are rotatable in their respective sockets afford a bearing of small area and reduce to a minimum the grinding action which would result if the parts 17, 19 and 24, 29 respectively made direct contact with 75 each other.

In order to lubricate the bearings of the balls 25 and 18 and thus still further contribute to the smooth running properties of the shaft, oil receptacles 31 and 33 are 80 formed respectively in the bell crank lever 26 and the extension 20, while passages 34 and 35 lead to the respective balls. The shaft bearings are provided with oil receptacles 36 and 37.

85 In operation rotation of the counter-shaft 2 causes actuation of the rod 8 and thereby oscillation of the bell-crank lever 26. The roll shaft 14 is thus positively actuated in one direction and yieldingly in the opposite 90 direction. The extent of the reciprocating movement is comparatively slight and does not interfere with the running of the belt 30 by which the roll shaft 14 is rotated.

The invention having been thus described 95 what is claimed and desired to be secured by Letters Patent is:—

1. A machine for buffering boots and shoes having, in combination, a rotary and reciprocatory roll-shaft, a buffering roll fast thereon, there being a free and unobstructed space beneath said roll to permit manual presentation of a shoe, two balls between which said shaft is held, a yielding member in contact with one of said balls and adapted when permitted to hold said shaft to one limit of its reciprocatory movement, a bell crank lever having a hardened plug in contact with the other ball, and means for oscillating said lever and thereby moving said 100 shaft in opposition to said yielding means.

105 2. A machine for buffering boots or shoes having, in combination, a shaft, a buffering roll mounted thereon, a lever pivoted to the frame and arranged when actuated to move 115 said shaft in one direction, a ball mounted between said shaft and lever, a spring arranged to act in opposition to said lever, a support for said spring, a rigid abutment, a ball mounted between said support and 120 abutment, and means for rotating said shaft and actuating said lever.

125 3. A machine for buffering boots and shoes having, in combination, a buffering roll, a rotary shaft upon which said roll is mounted, said shaft being provided with a cylindrical socket in one end thereof, a support slideable and rotatable in said socket, a spring

located in said socket and acting to force said support outwardly, a ball seated in the outer end of said support, an abutment having a corresponding seat for said ball, and
5 means for intermittently moving said shaft in opposition to the force of said spring.

In testimony whereof we have signed our

names to this specification in the presence of two subscribing witnesses:
